BASKET STRUCTURE FOR WASHING MACHINES

George Fields, Wilmette, Ill., assignor to Admiral Corporation, Chicago, Ill., a corporation of Delaware

Application June 21, 1945, Serial No. 600,802

5 Claims. (Cl. 210—76)

1

This invention relates to improvement in washing machines, and more particularly in an improved tub construction therefor.

In washing clothes or other articles, it has become recognized that the more desirable washing action is effected by circulating the washing fluid through the clothes. The more effective the circulation of the fluid through the clothes, the more efficient the washing operation. Heretofore, this has been effected in various manners by agitating the clothes in the water, by moving the container for the clothes, or by moving the water through the clothes. There has been, however, one zone in a washing machine to which relatively little attention has been directed. This is the zone at the wall of the tub. This zone becomes of particular importance in machines of the agitator type.

In automatic washing machines, where the clothes are spun for removing the water therefrom, a foraminous container is necessary in order to effect the water removing operation. Heretofore, it has been necessary to provide two complete tubs, an outer tub to retain the washing fluid in contact with the clothes, and an inner independent tub for spinning the clothes and removing the water therefrom. The space between these two tubs always had a tendency to accumulate dirt, lint and other extraneous matter, requiring the services of a service man or someone able to disassemble the machine to take the two tubs apart and clean the same.

The present invention contemplates a structure wherein the clothes are held away from contact with the imperforate water retaining tub by a liner or sub-wall which is perforated or foraminous. It also contemplates a means whereby the liner may be quickly and easily removed without the use of tools by those inexperienced in mechanics. The present invention enables such a construction to be utilized and also contemplates so arranging the parts that they are not loose when in position, preventing rattling thereof, and also presenting a surface which will not be damaging to the clothes during the washing operation.

The invention is particularly useful in washing machines of the type wherever the clothes are freed from water by a rotating motion of the tub although it is by no means limited to this particular type of structure since it will appear it is useful in washing machines having stationary tubs.

Another feature of the invention contemplates

2

the more effective and easy cleaning of the space between the outer tub and the liner to remove the accumulation of sediment and foreign material which becomes lodged therein and which definitely effects the efficiency of its operation.

Although I am about to describe the invention particularly in connection with its use in machines having vertically disposed tubs, it will be apparent that it is equally useful in tubs that are inclined from the vertical axis or are disposed on a longitudinal axis, and that the description of the specific embodiment is for the purpose of clarity of explanation and not to be considered as a limitation on my invention.

Still other advantages of the invention, and the invention itself, will become more apparent from the following description of an embodiment thereof, which description is illustrated by the accompanying drawings and forms a part of this specification.

In the drawings:

Fig. 1 is an elevational view of a washing machine with a portion of the outer casing broken away to disclose the inner tub, certain otherwise hidden parts being shown by dash lines;

Fig. 2 is an enlarged vertical medial sectional view through the tub of my invention, taken on the line 2—2 of Fig. 4;

Fig. 3 is a fragmentary section taken on the line 3—3 of Fig. 2; and

Fig. 4 is a fragmentary plan view of the tub with certain parts being broken away to more clearly show the structure underneath.

In carrying out my invention, I preferably provide an outer imperforate tub including a bottom or end wall and having a side wall extending therefrom. The side wall preferably slants outward but may be cylindrical if desired. A liner is provided for the tub, being made in segments which are held in the tub at the bottom end by engagement with a suitable member carried by the bottom or end wall. The top edge of the side wall may have a flange or ring carried thereby, and the upper ends of the segments frictionally engage this ring.

More specifically, as shown in the drawings throughout which like parts have been designated by like reference characters, my invention is illustrated as applied to a vertical spinner type of washing machine. In Fig. 1, there is shown a casing 10 which is supported on legs 11. The casing may be of any desired type preferably one which retains the water which is spun from the clothes.

55 A transmission mechanism may be housed in a

case 12 suspended below the casing and provides means for selectively driving an agitator or the tub as desired.

The transmission connects by a shaft and sleeve 14-15 to an agitator crank 16 and the tub 17 respectively. An agitator 18 may be disposed in the tub adapted to be driven by the crank 16 and may comprise any one of various types of agitators, the one illustrated in dash lines being one that is rotated in the tub.

The tub is preferably so disposed that the upper edge is below the top of the casing 10 which may be provided with a cover not shown.

The structure of the tub is more clearly shown in Figs. 2 to 4 inclusive. As more clearly shown in Fig. 2, the sleeve 15 is provided with a flange 20 at its upper end. The sleeve 15 extends through a central aperture in the bottom of the tub, and the flange is secured in driving relation to the tub by screws 21, the heads of which are countersunk in the flange, and the shanks of which extend through openings in the flange and tub and are threaded into a bracing member 23 on the underside of the tub. Suitable gaskets may be provided at the point of connection of the flange with the tub to prevent leakage of water therethrough.

The bracing member 23 may be of generally disc shape provided with a widened base portion 24 which has a close fit with the sleeve 15 and slants upwardly to the bottom of the tub being secured thereto by bolts 26 which extend through openings in the tub and the edge of the disc, and are secured by nuts 27 on the under side.

The same bolts 26, are utilized to secure a ring 38 to the bottom inside of the tub. The ring is bent back over as indicated at 31 to provide a channel, the use of which will more clearly appear as the description proceeds.

As previously stated, the shaft 14 extends into the interior of the tub and is provided with a crank arm 16 for operating a suitable agitator. Seated on the top of the flange 20 is a disc 33 through which the shaft 14 extends and to the top of which is secured by screws 34 a disc 35. The disc 35 may extend to a point substantially midway between the center of the tub and the side wall, being spaced above the bottom of the tub; the edge terminates in a down-turned flange 36.

As previously stated, means is provided to hold the clothes spaced from the wall of the tub. Preferably, this means is a perforate liner formed of a plurality of segments, each of which is formed with a body portion 40 curved on a radius which permits it to be disposed in spaced parallel relation to the side wall of the tub and the bottom end of which likewise curves inwardly as viewed in the figures toward the disc 35. The sides of the body diverge from the bottom toward the top and are provided with flanges 41 on the sides and bottom, the edges of which are adapted to engage the side and bottom wall of the tub.

The contour of each segment is preferably the same and is such that when they are all placed in the tub, the flanges of each segment abut the other to provide a smooth interior surface against which the clothes may rest. In other words, the segments provide a false bottom and side for the tub which is supported and held in spaced relation from the bottom and side walls by the flanges 41.

The lower extremity of each segment is provided with a downwardly curved then outward-

ly extending lip which is engaged in the channel member 31, which thus holds the lower end securely in place. This lip may be continuous, but I have found that a preferred means comprises a pair of spaced lips or tongues 42 disposed at opposite sides of the segment. As will hereinafter appear, this structure facilitates assembly and disassembly of the structure.

Each segment is foraminous. The holes may be continuous over the entire surface if desired. I have, however, shown a preferred form where-in the holes are restricted to two zones, 43 being a zone at the bottom and 44 being a zone in the mid portion of the side wall between the top and the bottom. The holes may be formed in any suitable or desired manner. Adjacent the upper end of each segment the material is formed into a transversely extending boss 46 which protrudes toward the outer tub wall and thus serves to stiffen the member and hold it against deformation due to the weight of the clothes when they are being spun to dry them. The upper extremity of each segment is formed to provide an inwardly extending part 47 formed with a finger hole 48 therein. This provides a convenient means for engaging the segments with the fingers when it is desired to remove them.

As best illustrated in Fig. 3, the top of this portion is provided with an outwardly extending tongue 50 which may serve as means for frictionally holding the upper part of each segment in its proper position in the tub.

Referring to Fig. 2, there is shown a ring for the upper end of the tub which comprises a downwardly extending flange 52 disposed in spaced relation to the tub wall and secured thereto at spaced points (Fig. 4) by outward projections 53 which may be spot welded to the tub wall. The flange could also be secured to the tub wall by bolts or screws extending through the wall into the projections if desired. These projections are spaced regularly around the periphery of the tub and the space between projection provides passageways through which fluid thrown from the clothes may escape during the spinning operation.

The body of the ring then extends horizontally inwardly at 53 and then curves upwardly at 54 terminating in an outwardly curved edge or bead 55 which defines the central opening through which the clothes may be withdrawn or inserted into the tub.

The tongues 56 of the segments are adapted to frictionally engage with the underside of the portion 53 to hold the upper ends of the segments in the tub. If desired, the upper ends of the segments could be held by suitable bolts.

In assembling the segments are inserted by engaging the lips 42 in the channel 31, after which the top of the segment is rotated back against the tub wall with the tongue 56 engaged under the part 53.

The succeeding segments are also placed in the tub in a like manner with the flanges 41 juxtaposed to each other, the contour of the segments being such that when the last segment is in position, the segments constitute a complete liner for the side and most of the bottom wall of the tub.

The foraminous structure permits better circulation of water through the clothes. After the clothes are washed, the tub may be rotated about its axis, and the water passes out through the

holes 43—44 into the space behind the segments. It is then forced upwardly due to the inclination of the tub wall where it passes through the openings between the projections 56 and is discharged to the outer container 10.

In course of time, sediment and other foreign material becomes lodged behind the segments. At this time, the segments may be quickly removed by placing a finger in the opening 48 and pulling the top of the segments toward the center of the tub and removing the lips or tongues from the channel 31. The segments being removed, the accumulation of material may be easily and quickly rinsed off and the segments replaced.

It will thus be seen that I have provided an improved tub for a washing machine which assists in the washing and drying of the clothes. The improved structure is easy to remove and replace by those mechanically unskilled and without the use of tools. Because it is easy to remove, it facilitates the cleaning of the machine, make accessible heretofore inaccessible places which lends itself to more efficient operation as well as increased sanitation.

Having thus described my invention in an embodiment thereof, I am aware that numerous and extensive departures may be made therefrom without departing from the spirit or scope of the appended claims.

I claim:

1. A washing machine comprising a housing, a tub supported within said housing and including an end wall, a side wall extending from said end wall and having an open end, a member carried by said end wall and spaced therefrom and having a free edge, a plurality of foraminous segments adapted to be disposed in spaced relation to said side wall with the ends held by said free edge, said segments being disposed with their edges in wedging engagement with each other to hold them in position and provide a substantially continuous liner each of said segments having outwardly extending ribs for engagement with said tub wall and to hold them spaced from said wall.

2. A washing machine comprising a housing, a tub disposed within the housing and comprising an end wall and a side wall extending from said end wall to provide an open end for said tub, a ring secured to the side wall adjacent the open end, a liner for holding the material to be washed in spaced relation to said walls comprised of a plurality of removable segments, each segment being foraminous and formed with edge flanges for engagement with said side and end walls and to hold said segments in spaced relation to said walls, said segments adapted to be disposed with the edge flanges in juxtaposed relation to each other, means to hold the ends of said segments to the end wall, the other ends of said segments adapted for engagement with said ring, said segments being provided with projections extending circumferentially relative to the side wall for holding the ends of said segments in spaced relation thereto.

3. A washing machine comprising a housing, a tub disposed within the housing and comprising an end wall and a side wall extending from said end wall and formed to provide an open end for said tub, a ring secured to the said tub adjacent the open end at spaced intervals therearound and formed to provide fluid escape passages at the outer edge thereof, means for holding the material to be washed in spaced relation to said walls comprising a liner having its edge extending

in spaced relation from the side wall above said end wall, said liner comprised of a plurality of removable segments provided with foraminous zones, each segment having edge flanges for engagement with said side and end wall and to hold said segments in spaced relation to said walls, means to hold the ends of said segments to the end wall, the other end of said segments adapted for engagement with said ring, said segments being provided with a projection extending circumferentially relative to the side wall for holding the ends of said segments in spaced relation thereto.

4. A washing machine comprising a housing, a tub mounted for rotary movement in said housing comprising an end wall and a side wall extending from said end wall at an angle slightly greater than 90° and formed to provide an open end for the tub a member secured to said tub at the open end thereof and comprising a ring secured to the side wall at spaced intervals therearound and formed to provide fluid escape passages at the outer edge of the ring, means for holding the material to be washed in closely spaced relation to said walls comprising a liner, a member secured to the end wall and having its edge extending in spaced relation from the side wall above said end wall, said liner comprised of a plurality of removable segments, each segment being formed with edge flanges for engagement with said side and end wall and to hold said segments in spaced relation to said walls, said segments adapted to be disposed with the edge flanges in juxtaposed relation to each other to form a substantially continuous sub wall, said member adapted to hold the ends of said segments to the end wall, the other end of said segments adapted for wedging engagement with the underside of said ring and formed with projections extending away from said side wall, said projections each formed with a finger hole which may be engaged to remove the segments by moving them inwardly away from the side wall, said segments being provided with a projection extending circumferentially relative to the side wall for holding the ends of said segments in spaced relation thereto, said segments being provided with a foraminous zone spaced intermediate the ends of the side wall and a second zone disposed opposite the end wall.

5. A washing machine comprising, a housing, a tub disposed within the housing and comprising an end wall and a side wall extending from said end wall to provide an open end for said tub, a ring secured to the side wall adjacent the open end extending inward from the side walls and defining an opening of less diameter than the side wall, a liner for holding the material to be washed in spaced relation to said side wall comprising a plurality of removable segments, each segment being foraminous and formed with outwardly extending flanges for engagement with said side wall for holding them in spaced relation thereto, said segments adapted to be disposed with their longitudinal edges in juxtaposed relation to each other, means to hold the segments to the end wall, the other ends adapted for engagement with said ring, said liner when in position having a diameter greater than that of the opening in the ring.
